ABSTRACT OF THE DISCLOSURE

A ferrite memory comprises: a plane block made of ferrite; a first network of parallel wires deposited on the block; an insulating layer deposited over this network, and a second network of further parallel wires, intersecting the wires of the first network; a ferromagnetic layer covers the block and the first and second network; a further layer of dielectric material insulates this ferromagnetic layer from the conductors of the first and the second network.

The present invention relates to the manufacture of ferrite wafer memories.

It is known to use for the manufacture of such memories a grooved ferrite block into which the control wires are fitted and which is assembled together with a ferromagnetic layer of an iron-nickel alloy deposited on a glass substratum. This results in a structure having a certain air-gap and therefore a certain fragility and a somewhat defective protection against external effects.

It is an object of this invention to provide a more robust memory with better protection against external factors in which the gap is filled with an insulator.

According to the invention there is provided a ferrite memory comprising a ferrite plane block; a first network of parallel conductors on said block; a second network of parallel conductors on said first network intersecting said first network, said parallel conductors of said second network being insulated from said parallel conductors of said first network; and a ferromagnetic layer covering said block and said first and second networks, said layer being insulated from said parallel conductors of said networks.

For a better understanding of the invention and to show how the same may be carried into effect reference will be made to the drawings accompanying the following description and in which:

FIG. 1 shows a plan view of a ferrite block prior to the removal of the superfluous insulating material;

FIG. 2 is a cross-section along the line I—I of the block in FIG. 1;

FIG. 3 is a perspective view of the ferrite block after the removal of the surplus insulating material; and

FIG. 4 is a cross-section along the line II—II of the block of FIG. 3 after the depositing of the ferro-nickel layer.

The same reference numerals designate the same elements throughout all the figures.

2

FIGS. 1 and 2 show, in plan view and in cross-section respectively, a ferrite block 1 according to the invention prior to the removal of the superfluous insulating material. On the ferrite block 1 is deposited a network of parallel conductors 2, for example by evaporating under a vacuum, and then an insulating layer 4. In the case of evaporation under a vacuum, this layer will preferably be of silica. Next a second network of conductors 3 is deposited at right angles to the first network and then a second layer of insulating material 5. The insulating material is then removed where there are no conductors, and a block of the type shown in perspective in FIG. 3 is obtained. On this prepared surface of the ferrite block, a ferromagnetic layer of an iron-nickel alloy 6 is deposited, for example by electrolysis. The ferromagnetic layer 6 assumes the shape of this surface, as shown in FIG. 4.

Of course the invention is not limited to the embodiment described and shown which was given only by way of example. In particular, the insulating and ferromagnetic layers may be applied by any known method without thereby departing from the invention.

What is claimed is:

1. A ferrite memory comprising a ferrite plane block; a first network of parallel conductors on said block; a first network of insulating parallel strips covering respectively said conductors and a second network of parallel conductors on said first network intersecting said first network, said parallel conductors of said second network being insulated by said insulating parallel strips from said parallel conductors of said first network; a further network of insulating parallel strips covering respectively said conductors of said second network; a ferromagnetic layer covering said block, said insulating parallel strips and said further insulating network.
2. A ferrite memory as claimed in claim 1, wherein said ferromagnetic layer is of an iron-nickel alloy.
3. A ferrite memory as claimed in claim 1, wherein said first and second networks intersect at right angles.
4. A ferrite memory as claimed in claim 1, wherein said networks are insulated from each other by means of silica.
5. A ferrite memory as claimed in claim 1, wherein said networks are insulated from said layer by means of silica.
